HEDGE TRIMMER

Richard Steele Hart, Wheaton, Ill., assignor to Sunbeam
Corporation, Chicago, Ill., a corporation of Illinois

Filed Sept. 21, 1965, Ser. No. 87,092

Term of patent 14 years

(Cl. D40—1)

FIG. 1 is a perspective view of a hedge trimmer embodying my new design;

FIG. 2 is a top plan view thereof;

FIG. 3 is a side elevational view thereof;

FIG. 4 is a bottom plan view thereof; and

FIGS. 5 and 6 are front and rear elevational views, respectively thereof.

The dominant features of our design reside in the portions shown in full lines.

The blade member illustrated in broken lines in FIG. 1 has been omitted in FIGS. 2-6 for convenience of illustration only.

I claim:

The ornamental design for a hedge trimmer, as shown and described.
